AXEL GUSTAF EMANUEL HULTGREN, OF GOTTERNBOORG, SWEDEN, ASSIGNEE TO
AKTIEBOLAGET SVENSKA KULLAGERFABRIKEN, OF GOTTERNBOORG, SWEDEN,
A CORPORATION OF SWEDEN.

METHOD OF AND MEANS FOR HEATING BALLS.

1,342,171.

Specification of Letters Patent. Patented June 1, 1920.

Application filed October 4, 1919. Serial No. 328,512.

To all whom it may concern:

Be it known that I, AXEL GUSTAF EMANUEL HULTGREN, a subject of the King of Sweden, residing at Gottenborg, in the Kingdom of Sweden, have invented new and useful Improvements in Methods of and Means for Heating Balls, of which the following is a specification.

This invention relates to a method of and means for heating balls, especially metal balls, and its object is to effect automatic feed as well as effective and uniform heating of a great number of balls simultaneously, while using a furnace of simple construction and, owing thereto, reliable and durable, said furnace utilizing at the same time in a rational manner the heat supplied.

The invention is based on practical experiments of feeding balls through a furnace in an uninterrupted row, the movement of the balls in said furnace being effected either by the gravity or by a pressure influencing the balls at the inlet end of the furnace or by both of said forces. The conditions to be fulfilled in order that such a feeding shall be realized have proved to be as follows: The balls are to be arranged so as to touch one another on all sides and to form straight rows in three directions forming angles of 30 60° with one another; furthermore one of said three directions should be parallel to or form right angles with the feed direction, and the mutual contact of the balls in each row has to be undisturbed. To this purpose it will, obviously, be necessary that a certain pressure be maintained between the balls in the longitudinal as well as in the transverse direction of the row. In the experiments made a sloping bottom of a furnace was used as runway for the balls, and the pressure between the balls in the longitudinal direction of the runway was effected by placing at the fore end thereof a transverse obstacle in the form of a wall which 45 the balls had to pass before leaving the furnace. The necessary lateral pressure was effected by providing the runway with lateral edges serving as guides, the distance between said lateral edges being adjusted according to the diameter of the balls. The 50 same result could, however, have been attained by constructing the runway with an angular or curved cross-section, the balls then

effecting by their own weight the necessary lateral pressure. As a general condition it 55 was ascertained that the runway should have the form of a general cylinder having the generatrix parallel to any of the three main directions of the balls in the row mentioned above.

In the beginning the experiments were performed with the furnace and the balls in a cold state, and in this case no difficulties were met with in maintaining the necessary contact between the balls in the row. 60 When heating the furnace and the balls, it was, however, evident that the frictional relations between the hot balls as well as between them and the runway varied to such an extent that it was impossible to determine the inclination of the runway most suitable to the feed at a moderate feed pressure. On account thereof the feed pressure was sometimes too great, causing some balls to be pressed out of the row, the connection 65 between the balls thus being disturbed and further feeding impossible. The object desired viz. automatic feed as well as effective and uniform heating of a great number of balls simultaneously could not, consequently, 70 be attained in this manner.

The inconvenience above stated is avoided, according to this invention, by dividing the balls in the row into several consecutive groups separated by frames or the like propagating the feed pressure independently of the balls of each separate group. In order to assure an effective and uniform heating of the balls the bottom of the furnace should preferably be so inclined that an accurate 75 rolling motion of the balls is obtained, this effect being facilitated by the fact that, owing to the division of the balls into several independent groups, the pressure and the friction between the separate balls will 80 be smaller than in the uninterrupted row.

A preferred embodiment of the invention is illustrated in the accompanying drawing in which:—

Figure 1 is in part a vertical section and 100 in part a side view of a furnace for hardening of balls. Fig. 2 is a plan view partially in section of the furnace and Fig. 3 is a cross section of the body of the furnace.

Referring to the drawings, the furnace 105 consists of an elongated channel 1 of brick-

work provided at the outlet end 2 with gas burners 3 for heating the furnace to the necessary temperature increasing toward said end. The channel 1 has a freely supported bottom 4, the inclination of which is equal, or approximately equal to the angle of rolling friction during the present conditions, the balls 5 to be heated being caused to roll on the bottom. The balls 10 fill, practically taken, the whole bottom and are divided according to the invention into several groups independent of one another and separated by frames 6 movable along the bottom. The feed of the frames 6 together 15 with the balls 5 is effected by a driving mechanism placed at the inlet end 7 of the furnace. Said mechanism consists of a frame-work 9 secured to the frame 8 of the furnace and movable in the feed direction by means of two cam disks 11 and 12 fast on a rotary shaft 10 and engaging rollers 13 journaled in the frame-work 9. The shaft 10 is driven by the aid of an electro-motor 14 attached to the frame 8, a worm gear 15 and a chain gear 16. The movement of the frame-work 9 in opposite direction is effected by a weight 17 connected by means of a cord 18 or the like guided by a roller 19 with the fore part of the frame-work 9. 20 Attached to the bottom 4 of the furnace at its outlet end are two guide-rails 20 and 21 extending out of the furnace through an opening 22 for guiding the frames 6, when ejected by gravity from the furnace. The 25 opening 22 is normally closed by an automatically working door 23. The frames 6, upon leaving the furnace, are stopped by the upwardly bent ends of the rails 20 and 21, then removed for instance by hand and, 30 preferably, while hot, replaced on the bottom of the furnace at the inlet end, then refilled with balls and fed anew into the furnace. In close connection with the outlet end 2 is disposed a channel 24 closed 35 on all sides and extending below the surface of the hardening bath 25 so as to form in a well-known manner a liquid seal preventing cold air from entering the outlet end of the furnace. As the frames 6 reach 40 the rails 20 and 21, the balls 5 heated to the necessary temperature fall down between and at the sides of said rails and are guided by the channel 24 to the hardening bath 25 in which they are cooled and hardened. The 45 portion 26 of the bottom 4 situated at the outlet end 2 is horizontal or approximately horizontal, and consequently, when the fore edge of a frame 6 extends outside said portion 26, no free rolling of the balls in the 50 feed direction can take place. By this it is attained, that the balls of each group cannot pass simultaneously but successively that edge of the bottom, thus causing all the balls to attain the same degree of heat. 55 The feed of the frames 6 together with

the balls 5 which takes place with a velocity adjusted to the necessary degree of heat can be effected instead of by the mechanism shown, for instance by the frames 6 being interconnected so as to form an endless chain moving continuously through the furnace. The filling of the balls into the frames may be effected in any manner, for instance by hand or automatically from any suitable magazine. 70

Having now particularly described and ascertained the nature of my said invention and in what manner the same is to be performed, I declare that what I claim is:—

1. The method of heating balls, consisting 80 in rolling the balls arranged in a series of successive groups, spaced one from the other, through a heating medium.

2. The method of heating balls, consisting 85 in placing the balls on the bottom of a properly heated furnace channel, dividing the balls transversely of the channel into a plurality of groups by means of separating devices, and forwarding the balls along the said channel by the application of a driving force applied to said separating devices independently of the balls. 90

3. The method of heating balls as set forth in claim 2 which consists in causing the balls to roll along the bottom of the channel during 95 their forward movement.

4. Means for heating balls, comprising a furnace channel adapted to be heated to the desired temperature for containing balls and a plurality of separating devices placed in 100 said channel for dividing the balls into consecutive transverse groups, and means active upon the said separating devices for moving the same and the balls through the furnace channel. 105

5. Means for heating balls, comprising a furnace channel having a bottom for supporting the balls and means for heating same, a plurality of frames placed in a consecutive row and on said bottom for dividing the balls transversely into groups, and means active upon the frames for moving the same and the balls along said bottom. 110

6. An apparatus as set forth in claim 5, comprising a mechanical operating device 115 adapted to engage the aftermost frame of the series and force the frames and the balls through the furnace.

7. Means for heating balls, comprising a furnace channel and means for heating the same, said channel having a bottom adapted to receive a plurality of balls, a series of frames each adapted to inclose upon all four sides a series of balls, and dividing the mass of balls transversely into groups, the frames throughout the series being in engagement one with the other, and mechanism adapted to engage the frames and move the same through the furnace channel. 120

8. A heating furnace, comprising a chan- 125

nel having a bottom for receiving a plurality of balls, a plurality of frames placed in a consecutive row on the said bottom for dividing the balls into groups, means for moving the frames and balls along said bottom and through the channel, the bottom of the furnace being provided with a discharge opening, and means located adjacent said discharge opening for guiding the frames 10 out of the furnace and permitting the balls to pass through the discharge opening.

9. Means for heating balls, comprising an inclined furnace channel having a discharge opening and provided with a bottom inclined toward the discharge opening, there being an upward inclination of the said bottom immediately adjacent said discharge opening to arrest the rolling motion of balls transversing said bottom upon approaching 20 said opening.

10. Means for heating balls, comprising an inclined furnace channel having an outlet means for causing the balls in said channel to roll along said bottom, and means adjacent the outlet of the furnace for retarding the rolling motion of the balls at 25 said end.

11. Means for heating balls, comprising a furnace channel having an inclined bottom 30 upon which the balls are adapted to roll, the inclination of said bottom being equal or approximately equal to the angle of rolling friction during the heated condition of the balls, and means for dividing the balls into 35 transverse groups and isolating the balls in

each group from the accumulated pressure of the mass of balls.

12. The method of heating balls, consisting in placing the balls on the bottom of a properly heated furnace channel, dividing 40 the balls into a plurality of groups by means of separating devices, and forwarding the balls along said channel by the application of a driving force applied to said separating devices independently of the balls, the balls 45 of each group being arranged to form straight rows in three directions forming angles of sixty degrees with one another and one of said three directions being parallel to or forming right angles with the feed 50 direction.

13. The method of heating balls as set forth in claim 12, which consists in causing the balls to touch one another on all sides and roll along the bottom of the channel 55 during their forward movement.

14. Means for heating balls comprising elements for supporting the balls, a plurality of separating devices for dividing the balls into groups and means active upon said 60 separating devices for moving the same and the balls through the heating means.

15. Means for heating balls comprising elements for supporting the balls, and a plurality of separating devices for dividing 65 the balls into groups.

In testimony whereof I have signed my name.

AXEL GUSTAF EMANUEL HULTGREN.
